Primary Examiner — Katherine Glennon*(74) Attorney, Agent, or Firm* — Thedford I. Hitaffer; Hitaffer & Hitaffer, PLLC(57) **CLAIM**

The ornamental design for a fastener with depth gauge, as shown and described.

DESCRIPTION

FIG. 1 is a front perspective view of a fastener with depth gauge.

FIG. 2 is a rear perspective view of the fastener shown in FIG. 1.

FIG. 3 is a right side elevational view of the fastener shown in FIG. 1.

FIG. 4 is a left side elevational view of the fastener shown in FIG. 1.

FIG. 5 is a bottom plan view of the fastener shown in FIG. 1.

FIG. 6 is a top plan view of the fastener shown in FIG. 1.

FIG. 7 is a front view of the fastener shown in FIG. 1; and,

FIG. 8 is a rear view of the fastener shown in FIG. 1. The broken lines show portions of the fastener with depth gauge that form no part of the claimed design. The fastener with depth gauge is shown with symbolic breaks in its length; the appearance of any portion of the article between the break lines forms no part of the claimed design.

1 Claim, 5 Drawing Sheets(56)
